RAIN CAPE

Anne Klein, 165 E. 66th St., New York, N.Y.

Filed May 27, 1964, Ser. No. 80,187

Term of patent 14 years

(Cl. D3—3)

FIG. 1 is a side perspective view of a rain cape, showing my new design as it appears when worn;

FIG. 2 is a front perspective view thereof; and

FIG. 3 is a top plan view of the inside of the rain cape with the fastener of the hood portion in an open position.

I claim:

The ornamental design for a rain cape, substantially as shown.
